UNITED STATES PATENT OFFICE

GEORGE W. HENRY, JR., OF PHILADELPHIA, PENNSYLVANIA, ASSIGNOR TO SOABAR COMPANY, OF PHILADELPHIA, PENNSYLVANIA, A CORPORATION OF PENNSYLVANIA

CLIP FORMING MECHANISM

Original application filed August 20, 1930, Serial No. 476,647, now Patent No. 1,879,233, dated September 27, 1932. Divided and this application filed August 13, 1932. Serial No. 628,735.

My invention relates to certain improvements in means for securing tickets to merchandise. This application is a division of an application filed by me on August 20, 1930, Serial No. 476,647, which resulted in Patent No. 1,879,233, dated September 27, 1932.

The object of this invention is to provide means for bending a clip into U-shape form and to press the prongs of the clip onto one surface of the ticket, and to bend the U-shaped portion so as to press said portion against the material and force the material into a slot or other shaped opening in the ticket. The invention can be used in connection with the machine set forth in the above application or may be used as an independent means for securing a ticket to the material without puncturing the material.

In the accompanying drawings:

20 Fig. 1 is a sectional view of sufficient of the device to illustrate the invention, the parts being in the open position and the ticket and the material placed in position on the support;

25 Figs. 2, 3 and 4 are views showing the steps in the process of bending the clip and attaching it to the material and the ticket;

Fig. 5 is a sectional view on the line 5—5, Fig. 3, showing the dies for bending a wire 30 into U-shaped form;

Fig. 6 is a plan view of Fig. 5;

Fig. 7 is a perspective view of the forked die for bending the wire into U-shaped form;

Fig. 8 is a perspective view of the lever 35 which holds the wire while it is being bent to form the loop;

Fig. 9 is a perspective view of the presser foot for pressing the clip onto the ticket;

Fig. 10 is a perspective view of a slotted 40 ticket;

Fig. 11 is a perspective view showing the ticket applied to the material;

Fig. 12 is a perspective view of the material and ticket showing the clip pressing the 45 material into the slot in the ticket;

Fig. 13 is an enlarged sectional view of the ticket and fabric, showing the clip in the final position, the looped portion of the clip forcing the material into the slot of the ticket;

50 Figs. 14, 15 and 16 are diagrams showing

the steps in the forming of the wire to produce the clip which secures the ticket to the material.

a is a ticket of any suitable form, having a slot a—1 in the present instance, the slot 55 being near one end of the ticket. b is the fabric to which the ticket is applied. x is the wire, which is first bent into U-shaped form as shown in Fig. 14. This wire is then bent as in Fig. 15, the prongs being spread apart 60 and pressed upon the upper surface of the ticket on each side of the slot, and then the clip is bent as shown in Fig. 16, in which the looped portion of the ticket is bent under the material and the cross bar, the cross bar 65 being in line with the slot of the ticket and the final step is to press this U-shaped portion of the ticket against the fabric so as to force the fabric into the slot in the ticket, thus holding the ticket firmly to the material 70 without puncturing the material.

Referring now to Fig. 1, the wire x in the present instance passes through a throat in the block 42 and is sheared by a shearing die 43 which is slotted at 44, the lower edge of 75 the slot forming the cutter. This shearing die is actuated by any suitable means. The means for bending the cut section of wire consists of a vertical movable forked die 52. The forks of the die are slotted at 53 to receive and guide the wire while it is being bent. This die may be controlled by a suitable cam as in the above application. In order to hold the wire x while it is being formed by the forming die 52, a lever 59 is 80 so located that the hooked arm 60 of the lever extends over the forming die 52 and over the wire as in Fig. 1, so that when the forming die is raised the hooked arm 60 of the lever will remain stationary at the center of the 85 cut section of the wire as in Fig. 2, the lever 59 being connected to a cam operating mechanism by a rod 61 to mechanism actuated by any suitable mechanism such as a cam. After the loop is formed in the wire as shown 90 in Figs. 2 and 14, the prongs x—1 of the clip are bent over the ticket by the presser foot 65, Fig. 3, while the looped portion is held by the die 52. This movement forces the ticket firmly onto the fabric and onto the 95 100

support 40, holding the ticket and fabric while the lever 74, Fig. 4, engages the looped portion of the clip and forces it against the material. The short arm of the lever has a 5 lip 75 which forces the loop end $\alpha-2$ of the clip into the slot in the ticket, carrying with it the fabric under the slot, as shown in Fig. 4, fastening the ticket firmly to the material. The lever 74 is pivoted at 76, and the long 10 arm of the lever is connected by a link 77 to mechanism actuated by a cam or other device as shown in the above-mentioned application. This completes the operation of the machine and when the parts are in the position shown in Fig. 1, the fabric with the ticket attached can be removed and another piece 15 of fabric and a ticket can be placed in position, and the operation above described can be repeated.

20 In the application referred to above, this mechanism is claimed in connection with a machine for applying tickets to merchandise which includes means for feeding a strip of tickets through a machine, and means for 25 feeding wire to a bending mechanism. The present application is intended to cover the means for forming and bending the clip as the device can be used not only with the machine of the application referred to above, 30 but can also be used for applying independent tickets to pieces of fabric.

An application for Patent No. 363,605, filed by me on May 16, 1929 and allowed July 12, 1932, covers the particular form of clip.

35 I claim:

1. The combination in a mechanism for bending a clip and securing it to material, said means consisting of a die for forming the clip into U-shaped form with the prongs 40 extending above the line of the material and the ticket to which it is to be secured; a presser foot for pressing the prongs of the clip onto the surface of the ticket while the U-shaped portion is held by the die; and 45 means for pressing the U-shaped portion under the material after the die has been retracted and while the prongs are held by the presser foot.

2. The combination in a mechanism for 50 bending a clip and securing it to a slotted ticket and material, said means consisting of a die for forming the clip into U-shaped form with the prongs extending above the line of the ticket and material to which it is to be 55 secured; a presser foot for pressing the prongs of the clip onto the surface of the ticket while the U-shaped portion is held by the die; and means for pressing the U-shaped portion under the material after the die has 60 been retracted, the end of the U-shaped portion pressing the material into the slot in the ticket while the prongs are held by the presser foot.

3. The combination in mechanism for 65 bending a clip and securing it to a slotted

ticket and material, of a support for the material and a ticket; a slotted die below the support and in line with the edge of the ticket for forming a wire into U-shaped form to produce the clip; a hooked lever for 70 engaging the wire and holding it while the U-shaped die is forming the clip; a presser foot for bending the prongs of the clip over and upon the ticket mounted with the material on the support; and a lever arranged to 75 engage the looped portion of the clip and force it against the material, the short arm of the lever having a lip which forces the looped end of the clip into the slot in the ticket, carrying with it the material under 80 the slot, thus securing the ticket firmly to the material without puncturing the material.
